UNITED STATES PATENT OFFICE.

WILLIAM L. RUNZEL, OF CHICAGO, ILLINOIS, ASSIGNOR TO RUNZEL-LENZ ELECTRIC MFG. CO., OF CHICAGO, ILLINOIS.

FLEXIBLE CORD.

1,340,839.

Specification of Letters Patent. Patented May 18, 1920.

Application filed May 19, 1917. Serial No. 169,616.

To all whom it may concern:

Be it known that I, WILLIAM L. RUNZEL, a citizen of the United States, residing at Chicago, in the county of Cook and State 5 of Illinois, have invented a certain new and useful Improvement in Flexible Cords, of which the following is a full, clear, concise, and exact description, reference being had to the accompanying drawings, forming a 10 part of this specification.

My invention relates to flexible cords and more particularly to that kind of a flexible cord made up of conducting elements for the purpose of furnishing flexible interconnection for current conducting purposes.

My invention has large application in connection with what are called switchboard cords, for instance, and I will describe herein my invention as applied to such 20 switchboard cords, this being for illustrative purposes as the application of my invention to equivalent uses will be readily apparent.

In the manufacture of switchboard cords, 25 for instance, where these have at least two separate and distinct conductors it is necessary to provide conducting means which are of course adequate for the purposes in hand. At the same time these flexible cords must 30 be so constructed that they will be capable of much hard usage. The very nature of the use of flexible cords makes it imperative that the wearing qualities are of the highest importance. The problem presented by 35 this state of things includes the proper selection of conducting elements flexible in their nature so that repeated bending will not destroy their continuity.

There has been developed in answer to 40 this demand a connecting cord in which at least one of these conductors is helically wound and some in which both conductors are helically wound. These conductors are made of steel or similar material, not be- 45 cause steel is the best conductor, but pri- mately on account of its ability to remain unbroken through a period of long continued use. In order to provide the necessary conductivity tinsel conductors made of 50 copper are frequently added and laid in metallic contact along the helical conductor.

My invention concerns itself with the provision of one or more conducting elements for a flexible cord, which shall have 55 the requisite conductivity without the nec-

essary reinforcement of tinsel or other auxiliaries, and which shall at the same time be able to maintain its character under the heavy service to which such cords are subjected. In this manner the use of composite 60 conductors or similar expedients is entirely avoided.

I have found that by the use of a helically wound phosphor bronze conductor I obtain in one element those necessary qualities hereinbefore discussed. The phosphor bronze conductor has the required conductivity and at the same time has the required durability.

My improved cord likewise has a feature 70 very desirable in this connection and that is to so arrange the cord that the conductors thereof each have an equal amount of resistance. It will be readily clear that when two helically wound conductors are used, one 75 wound about the other, that the diameter of the convolutions of the outer conductor is greater than the convolutions of the inner conductor. Hence the outer conductor has a greater amount of metal. If the two conductors were thus made of the same gage 80 wire the resistance of the outer conductor would be much larger than that of the inner conductor. Where auxiliary conducting elements are used in connection with helical 85 conductors, equalization may of course be effected in that way. When the cord how- ever, as in this invention, is designed to use merely two helically wound conductors (when applied to a two conductor cord for 90 instance) then these auxiliary conductivity increasing devices are absent. In order to balance a cord of this kind so that the conductivity of both conductors will be 95 the same, I construct the outer helical con- ductor of a wire of increased gage so that the resistance of this outer conductor, even though the conductor is longer than the inner conductor will be the same or substan- tially the same as that of the inner con- 100 ductor.

In the accompanying drawing I illustrate one form in which my invention may be embodied. In this drawing—

Figure 1 is a side view of the cord of my 105 invention as applied to a two conductor cord showing the arrangement of the conductors and the various wrappings, and

Fig. 2 is a sectional view on line *a—a* of Fig. 1.

By referring to the drawing I show a central core 1 which is preferably of jute rope about which is helically wound the conductor 2 made of phosphor bronze. This 5 phosphor bronze conductor is of course very flexible, but very tough and has great durability under the service required of it. About this conductor 2 there is bound a suitable layer of insulating material such 10 as silk, cotton or wool, which again is surrounded by a braid 4 of somewhat similar material. About this is helically wound the conductor 5 likewise of phosphor bronze. This outer conductor, as will be apparent 15 has a larger diameter than the inner conductor 2. Thus by increasing the diameter of the outer conductor the resistance of the two conductors of the cord can be made the same even though the outer conductor has 20 convolutions of larger diameter than that of the inner conductor. About the conductor 5 there is then a suitable insulating wrapping 6, which may be moisture proof if desired, about which is placed the ordinary 25 covering 7 of insulation customary in cords of this nature.

It will thus be seen that the entire conducting portions of this cord are the conductors 2 and 5, these being helically wound 10 and formed of phosphor bronze wire. The two qualities of durability and conductivity

are thus combined in each of these elements 2 and 5 so that no other provision need be made in the cord for conducting purposes but merely for insulating purposes.

35

From what has been thus described the nature of my invention will be readily clear to those skilled in the art.

Having however thus described one form which my invention may take, what I claim 40 as new and desire to secure by Letters Patent is:

1. A flexible conducting cord of the character described comprising two concentric helically wound conductors, the outer conductor being larger in cross section than the inner conductor to equalize the resistance of 45 the two conductors.

2. A flexible conducting cord of the character described comprising two concentric 50 helically wound conductors made of phosphor bronze, the outer conductor being larger in cross section than the inner conductor to equalize the resistance of the two conductors.

55

In witness whereof, I hereunto subscribe my name this 13th day of April, A. D. 1917.

WILLIAM L. RUNZEL.
